TELEGRAPH RELAY

Victor John Terry, London, England, assignor to
 International Standard Electric Corporation,
 New York, N. Y., a corporation of Delaware

Application February 12, 1948, Serial No. 7,911
 In Great Britain January 24, 1947

Section 1, Public Law 690, August 8, 1946
 Patent expires January 24, 1967

4 Claims. (Cl. 200—166)

1

This invention relates to electro-magnetic telegraph relays of the type in which the tongue of the relay carries two contacts which move between two fixed contacts according to the movements of the armature of the relay and is particularly concerned with means for mounting the contacts.

The objects of the invention are to provide a relay in which chattering of the contacts against one another is reduced or eliminated and in which the change-over time can be made vanishingly small.

In the normal type of telegraph relay an armature of magnetised material is pivoted or held at one end in such a way that it can move between the two poles of an electro-magnet under the influence of signalling currents passed through the windings of the electro-magnet, commonly known as the relay windings. From the free end of the armature there is extended in line with the armature a strip (or strips) of metal known as the tongue and near the free end of the tongue two contacts are mounted, one on each side of the tongue and opposite one another, the contacts being so positioned that they lie between two fixed contacts carried on supports attached to the main frame of the relay. When the armature moves under the influence of signalling currents in the relay windings the contacts on the tongue are pressed against one or other of the fixed contacts.

The contacts which move when the armature moves will be referred to as the moving contacts while the contacts which are supported on the frame of the relay will be referred to as the co-operating fixed contacts. It is normal in using such relays to connect the positive pole of a signalling battery to one fixed contact and the negative pole of the same battery to the other fixed contact.

The tongue of the relay is connected to the line or apparatus into which the signals are to be relayed, the circuit being completed by a connection to the midpoint of the signalling battery. The purpose of the relay is to transmit square shaped signals corresponding to the signalling currents passing through the relay windings and with as nearly as possible the same time spacing as the original signals.

When the tongue of a relay such as is described above is thrown over to one side by a signalling impulse the moving contact tends to bounce off the fixed contact and a condition known as chattering is set up so that the current delivered by the relay is not steady as is desired but is inter-

2

mittent at least over the first part of each relayed signal.

Many devices have been introduced to overcome this chatter of which the general principle is that either the fixed contacts or the moving contacts or both, are so mounted that they can yield slightly under the pressure exerted by the armature. Yielding contacts of this type are usually mounted on springs.

10 Although mounting the contacts on springs effects an improvement some chatter still occurs at the moment of impact between the moving and fixed contacts and it has generally been found desirable to incorporate some method of dissipating in the form of heat the kinetic energy released at the moment of impact. This can be accomplished by arranging for the impact to be accompanied by friction between two members associated with the contacts.

15 It is always desirable that the response of the relay to changes of direction of the signalling current in the winding shall be, as nearly as possible, instantaneous. When the contacts of the relay are mounted on springs which yield under pressure, it is evident that when the current in the relay windings is reversed, there will be some movement of the armature during which the springs will keep the contacts together when they should ideally be open.

20 The electrical circuit through the other fixed contact cannot be established until the tongue has at least reached the neutral portion so that the outgoing signal from the relay will be slightly later in time than the received signal passed through the windings. This would not usually be of importance in itself provided an equal time delay occurred at each reversal. As however the received signalling currents through the windings do not build up to their maximum value instantaneously, the springs will be more deflected in the case of a signal of long duration than one of short duration and therefore the change-over time delays will vary, with the result that distortion will be introduced and the outgoing signals

25 30 35 40 45

will not be faithful replicas of the original signals.

50 55

By using the construction now proposed, the advantages of resilient contacts can be obtained, in conjunction with the frictional dissipation of the kinetic energy released at the moment of impact while the changeover time can be reduced at will, till the time of travel between contacts is zero, and, in fact, it can be reduced until the "make-before-break" facility is obtained, that is to say, that one of the moving contacts will be in contact with its co-operating fixed contact to-

wards which the relay tongue is moving before the other moving contact has become separated from its cooperating fixed contact.

The invention provides an electro-magnetic relay comprising an armature on which are mounted two contacts, said contacts being so positioned that they co-operate with two other contacts mounted on the static frame-work of the relay when the armature moves under the influence of signalling currents in the relay windings, characterised in this, that at least one pair of similarly acting contacts is mounted on a rigid support in such manner, that the two contacts of said pair are held a constant distance apart, said rigid support being carried in a resilient mounting so that any movement of one contact of said pair is accompanied by an equivalent movement of the other contact of said pair.

Various mechanical constructions can be devised for embodying the principles of the invention but only three embodiments will be described. The magnets, windings and armature of the relay are not illustrated as they do not form any part of the invention and may be of any suitable construction.

The invention will be understood from the following description taken in conjunction with the accompanying drawings in which:

Fig. 1 shows resiliently mounted contacts according to one embodiment of the invention.

Fig. 2 shows an alternative embodiment of the invention, and

Fig. 3 shows yet another embodiment of the invention.

In Fig. 1 there is shown a member 1 carrying two contacts 2, 3 mounted on a cylindrical extension 4 of a relay tongue 5. The tongue 5 is an extension of the free end of the magnetic armature of the relay, the tongue and armature being of any suitable construction. Under the influence of signalling currents in the relay windings the armature (not shown) and with it the tongue 5 moves to the right or left (as shown in the figure) as indicated by the arrows 6. The member 1 carrying the contacts 2, 3 will be referred to hereinafter as a spider. A hollow cylindrical hub 7 is an integral part of the spider. The cylindrical extension 4 of the relay tongue 5 has mounted on it a resilient bush 8 which bush may be made of any suitable resilient material such as, for example, natural or synthetic rubber. The inner surface of the resilient bush is firmly attached to the cylindrical extension 4 so that it is not free to rotate thereabout and the inner surface of the hollow cylindrical hub 7 of the spider 1 is firmly attached to the outer surface of the resilient bush 8, the two arms of the spider carrying the contacts 2, 3 being arranged so that the line through the two arms is perpendicular to the plane of movement of the armature indicated by arrows 6.

The two contacts 2, 3 project in opposite senses from the arms of the spider and constitute the moving contacts of the relay, co-operating with two fixed contacts 9, 10 adjustably mounted on the fixed framework of the relay. An electrical connection to the moving contacts is provided by means of a flexible connection 11.

From the above described construction, it follows that the spider will be given a small amount of rotational movement around the relay tongue when pressure is applied to the arms of the spider, owing to the elastic deformation of the resilient bush, and that the spider will return

to its normal position when the pressure is released.

In an actual construction, contact pieces of the usual type are mounted on the arms of the spider, one near the end of each arm, and so positioned that they project from the arms along lines which are parallel to the direction of travel of the tongue of the relay.

To understand the working of the relay, consider firstly that the tongue of the relay is in a neutral position with no current flowing through the relay windings. The fixed contacts may be adjusted so that there are only very small gaps between them and the moving contacts. If, now, a signalling current is passed through the relay winding, the armature and tongue will travel to one side and one of the moving contacts will press against its associated fixed contact and the spider will be rotated around the tongue through some small angle. The resilient bush yields sufficiently to minimise the tendency of the contacts to chatter, and owing to the nature of the material of the bush, a certain amount of damping is introduced by the natural internal friction of the material.

A further and perhaps more important advantage of this arrangement must, however, be noticed. As soon as one moving contact is pressed against its cooperating fixed contact, the spider commences to rotate. This causes the other moving contact to be given a movement away from its cooperating fixed contact in addition to the movement in the same direction due to the normal travel of the relay tongue. In other words the contacts open twice as fast as they would for the same speed of travel of the tongue in a conventional relay. This provides the feature of "quick break" which is a desideratum in all telegraph relay design. As soon as the current in the relay windings reverses, the pressure between one pair of contacts is released and the spider begins to return to its normal position so that the contacts which were open, will close together at twice the speed they would in the conventional relay. Thus the arrangement provides for a quicker make and a quicker break than has previously been obtained.

Consider now a relay employing this arrangement in which the fixed contacts have been so adjusted that they are both in contact with the moving contacts simultaneously when the tongue is lying in a neutral position. The instant current is applied to the relay windings, one pair of contacts will be pressed into firmer contact with each other while the other pair will immediately open. Thus it is possible with this arrangement to adjust the relay to give a zero change-over time or even a "make before break" facility without sacrificing the anti-chatter features provided by the use of resilient mountings for the contacts.

In this embodiment, as so far described, the spider is considered as being, in effect, a straight cross-piece with a cylindrical hub and contacts mounted near the two ends. It is not an essential feature of the invention that the resilient bush should be cylindrical and it may be found desirable to make the end of the relay tongue and the bush and the hub of the spider of some other shape, e. g. of elliptical cross-section.

In practice, the spider is not necessarily formed as a straight cross-arm but may be so shaped that the faces of the two moving contacts and the axis of rotation of the spider lie in one plane

at right angles to the direction of travel of the tongue.

If the damping provided by the internal friction of the material of the resilient bush is not considered adequate, additional frictional damping can be provided by arranging that the contact faces and the axis of rotation of the spider lie in a plane not at right angles to the direction of travel of the relay tongue. The rotational movement of the spider will then result in a sliding movement between the contact faces when they are pressed together. It has been found satisfactory to construct the relay with the plane containing the contact faces and the axis of rotation of the spider making angles up to 45° with the direction of travel of the tongue, in fact even greater angles have been found practicable.

The description of the above embodiment makes the principle of the invention clear and it is evident that the invention can be carried out in various different ways.

For example the spider could carry the "fixed" contacts and be resiliently mounted on the frame of the relay, the moving contacts being carried on a light cross-arm rigidly fixed to the relay tongue.

Another arrangement for carrying out the invention would be to mount the spider on the tongue of the relay employing a resilient bush, in such a way, that the axis of rotation of the spider was parallel to the axis of rotation of the relay armature. The two moving contacts would then be at different distances from the axis of rotation of the armature so the contact pressure on the two contacts would be different for equal signal current strengths in the relay windings. This could readily be compensated for by making the arms of the spider of unequal length.

Yet another embodiment of the invention is shown in Fig. 2. In this figure there is shown a part of a relay tongue 12 which moves with the armature under the influence of the signalling currents along the lines indicated by the arrows 13. The tongue carries at its free end a flexible extension in the form of a blade 14. A spider 15 is firmly mounted on the free end of the blade 14 and carries two contact pieces 16, 17. These contact pieces co-operate with two adjustably mounted fixed contacts. It can be seen that this arrangement differs from that shown in Fig. 1 only in that the resilient bush has been replaced by the flexible blade 14. The quick make and quick break and "make-before-break" facilities described above are obtainable in just the same way as with the embodiment described with reference to Fig. 1. However, the internal friction in the blade 14 does not provide as much damping as the resilient bush of Fig. 1. In order to increase the damping, leaf springs 18 (having one end fixed to the rigid part 12 of the relay tongue and the free end resting on the ends of the arms of the spider 15 as shown at 19) may be provided. When one of the contacts 16 or 17 is pressed against its cooperating fixed contact the spider will be rotated against the resilience of the blade 14 and friction will occur where the leaf springs 18 are resting against the ends of the spider 15. By suitably selecting the spring pressure and the flexibility of the blade 14 a damping effect equivalent to that obtainable with the resilient bush construction can be obtained with the advantage that the properties of the springs will not vary with time and use as is liable to occur with a resilient bush made of organic material.

A still further embodiment of the invention is

shown in Fig. 3. This requires a somewhat different mechanical construction although the principle involved is the same. In this case a straight lever 20 is pivoted at its mid point and carries the two moving contacts 21, 22, one at each end, both contacts being on the same side of the lever and so positioned that when the lever is displaced from the neutral position one moving contact, say contact 21, approaches a fixed contact 23 while the other moving contact is withdrawn from the other fixed contact 24.

The fixed contacts 23, 24 are themselves mounted on arms 25 attached to a rigid shaft 26, which is carried in bearings 27 and which lies parallel to the axis of the lever 20 when the latter is in its neutral position. It follows that any displacement of one of the fixed contacts must be duplicated by an equivalent movement of the other fixed contact. Springs 28 are fitted which restrain the movement of the fixed contacts and at the same time act as conductors thereto. Insulating material must be introduced at some point to separate the two fixed contacts electrically, and in the figure the arms 25 are shown as being made of an insulating material.

In this embodiment the resilience is supplied by the springs 28 restraining the movement of the fixed contacts and if frictional damping is necessary it can be provided by means of leaf springs 30 (not shown) resting on the arms 25.

In this embodiment the lever 20 may constitute the armature of the relay or may be actuated by the rotation of the spindle 29 which is itself under the control of the relay armature.

Although several embodiments have been described indicating different mechanical arrangements for carrying out this invention it is obvious that anyone skilled in the art can apply the invention in other ways.

40 What is claimed is:

1. An electro-magnetic relay comprising a frame member, an armature having an extension portion, a resilient bush of organic material firmly attached to said portion, a rigid cross-piece provided with an aperture through which said resilient bush is passed, the inner surface of the aperture of said cross piece being firmly attached to the outer portion of said bush, said cross-piece being mounted at right angles to the plane in which said armature moves, a first pair of contacts attached to said cross-piece near the ends thereof, said contacts projecting in opposite sense along lines parallel to the line along which said armature moves, a second pair of contacts mounted on said member, said last named contacts positioned to co-operate with said first named contacts.

2. An electro-magnetic relay comprising an armature adapted to move bi-directionally in response to received signalling currents, a rigid mounting member, means for resiliently attaching said mounting member to said armature, a first pair of stationary, opposed contacts, a second pair of opposed contacts, each attached to opposite sides of said mounting member in a plane parallel to the direction of movement of said armature and spaced on opposite sides of the plane of movement of said armature, one of the contacts of said second pair adapted to cooperate with one of the contacts of said first pair when said armature moves in one direction and the other of the contacts of said second pair adapted to cooperate with the other of the contacts of said first pair when said armature moves in the other direction, said mounting member adapted after

closure of corresponding of the contacts of said pairs to move in one angular direction and to move in an opposite angular direction after closure of the other corresponding contacts of said pairs, said angular movement being in a plane normal to the plane of movement of said armature and against the tension of said resilient means.

3. An electro-magnetic relay as claimed in claim 2, wherein said resilient means comprises an extension portion of said armature, said portion in the form of a thin, flexible and resilient blade, said mounting member attached to said portion at the end of said blade distant from the point of attachment to said armature.

4. An electro-magnetic relay as claimed in claim 3, further comprising damping means at-

5 tached to said armature and adapted to exert pressure against said mounting member.
